PORTLAND IRON WORKS, OF PORTLAND, OREGON, A CORPORATION OF OREGON.

KEY-OPERATED ACTUATING MECHANISM FOR ENGINE-GANGS.

1,102,419.

Specification of Letters Patent.

Patented July 7, 1914.

Application filed June 30, 1913. Serial No. 776,729.

To all whom it may concern:

Be it known that we, EDWARD E. McCLURE and ANDRE J. WOLFF, citizens of the United States, and residents of the city of Portland, county of Multnomah, State of Oregon, have invented a new and useful Improvement in Key-Operated Actuating Mechanism for Engine-Gangs, of which the following is a specification.

10 Contemporaneously with this invention we have invented a valve control for fluid engines fully set forth in the application filed by us June 30, 1913, under Serial Number 776,730, and this invention has for its 15 particular purpose the providing of key-operated mechanism by which such gang of engines may be controlled so as to be operated individually, or in gangs; the latter result being effected by previously placing 20 selected individual actuating mechanisms in a state for being actuated by a master-lever, or other master device, in one operation.

The advantage of previously selecting individual engines, of a gang of engines, and 25 then throwing the engines so selected into simultaneous action, by one operation of a master lever, is obvious.

We attain the desired result by the means illustrated in the accompanying drawings 30 and hereinafter fully described.

In the accompanying drawings: Figure 1 is a front elevation of our device, showing two banks of operating keys, the upper bank being the selecting keys for placing 35 the individual control-units in a state to be operated in gangs, simultaneously, and the lower bank being the keys by which control units may be operated individually; Fig. 2 is a right-end elevation of our device, partly in section, the direction in which certain parts will move being indicated by arrows; Fig. 3 is a front elevation showing the details of supplementary means for selecting a gang of control units in one operation and setting them for simultaneous operation; Fig. 4 is a vertical cross-section taken on the line 4-4 of Fig. 1, looking toward the left, showing the parts of one control unit; the unit being shown as thrown 45 from its inactive state into its active state (shown in broken outline) by pushing in the individual key of this unit. In connec-

tion with this figure is further shown a partial view of the valve element of the engine controlled and operated by this unit. Fig. 55 5 is a view similar to Fig. 4, illustrating the second phase of operation of a unit, the parts being here shown in the positions assumed by them after the depression of the master lever by which the selected control 60 units are operated. In this view the control unit is shown as used for opening and closing an electric switch, whereby an electro-magnetically operated valve is correspondingly opened or closed; Figs. 6 and 7 are 65 details of construction; and Fig. 8 is a plan section on the line A-A of Fig. 2.

Our device is built of a plurality of individual actuating mechanisms, corresponding in number with that comprised in the gang 70 of engines to be operated thereby, and each mechanism comprises the same parts and operates in the same way. These individual mechanisms are mounted in a case *a*. Fixed on the front and rear walls of said case are 75 longitudinal cleats, *b*, and on the front wall is also an angle iron *c* (see Figs. 4 and 5). The ends, *e*, of the case are provided with vertical slots, *f*, (see Figs. 2, 4 and 5) and on the outer face of each end is a lug *g*, in 80 which is threaded a set-screw *h*. Two parallel, longitudinal bars, *i*, *i*, preferably stiffened by webs *i'*, as shown in Fig. 6, slidably bear in the slots *f*. Plates, *j*, slide vertically in the guideways, *k*, on the exterior ends of 85 the case, and such plates *j* are bolted to the ends of the bars *i*, *i*. Thus when the plates, *j*, are moved up or down the bars, *i*, *i*, will be given a similar movement. Exterior of the ends of the case, *a*, and on the base, *r*, 90 are mounted hollow standards, *l*, inclosing each a coil-spring *m*, see Fig. 2. The inner walls of these standards are slotted as at *l'*, and the caps or tops of the standards are slotted in similar manner, so as to permit 95 the reciprocation of pins, *n*, which project from the plates, *j*, and extend through perforated bosses *o'* of the arms, *o*, of the master lever *p*; said arms being fulcrumed at *q* in the ends, *e*, of the case *a*. Normally 100 the master-lever, *p*, is supported in the position shown in Figs. 2 and 4, by the pins, *n*, resting on the coil-springs *m*. When the lever, *p*, is depressed, the sliding plates, *j*,

and the bars, i , i , will also be depressed, and when the master lever is released it is restored to its normal position by the springs m . Standards, r , are integral with the base, 5 r^2 , being arranged in parallel alinement. The base, r^2 , is mounted on the block r^3 . Fixed shafts, s , t , extending longitudinally and horizontally, are supported by the standards r , as shown in Figs. 4 and 5.

10 We will now describe the details of an individual actuating mechanism.

Fulcrumed on the shaft, s , is a lever u , made with toes u' , u^2 , and recess u^3 . On the shaft, t , is rotatably mounted a bell-crank 15 v having a portion v' and a recess v^2 . Connected to the bell-crank v is a rod w , extending through the rear wall of the case, a , to the operated mechanism. In Fig. 4 said rod connects with a wire w' connected to the 20 spring-controlled valve-arm w^2 of the valve w^3 , of which w^5 represents the stem. Let it be assumed that the valve is of the pneumatic type, and normally held open by the air pressure in the conduit, and such lift of 25 the valve exerts a pull on the ball-crank v , tending to rotate the same counter-clockwise. The spring w^4 acts as a compensator for any excessive movement. On the bars, i , i , are pivoted arms, y , z , having each a 30 hook-portion y' , z' , adapted to engage with the toes, u' or u^2 , of the lever u . The arms, y or z , are connected by a tie-rod, l^2 , so that they will move together, and, in consequence, when one of such arms is in its active 35 position, that is, adapted to engage with its related toe u' or u^2 of the lever, u , the other will be in its inactive position, in which it cannot engage its related toe of such lever. This action is evident from a 40 study of Figs. 4 and 5.

The movements of the arms, y , z , are limited by the cleats, b , b , affixed on the inner sides of the case a . All the arms, y , z , of all the individual actuating mechanisms 45 are positioned as in Fig. 4, by lifting the master-lever p into contact with the set-screws h , for in so doing the toes z^2 on the lower end of the levers z strike the trip-plate c , located at the front side of the case, 50 which causes the arms, y , z , to be tilted forward, to the left. When the arms, y , z , are so positioned the individual actuating mechanisms are in their inoperative state, and the act of depressing the master-lever will have 55 no effect. To understand this state, let it be assumed that the individual actuating mechanism is arranged as shown in Fig. 4. The movement or lifting of the master-lever p above its normal position is limited by its 60 arms, o , contacting with the set-screws h .

The arms, y , z , are placed in their active position (shown by the broken lines in Fig. 4) by operating their selector key 2. This key is fulcrumed on a pintle d in the cover 65 of the case a , and has a pendent leg 3 so

arranged that when the key 2 is depressed, such leg will strike against the back of the arm z and throw the arms, z , y rearward, to the right. When the arms, y , z , are so arranged, and the lever, u , is positioned as 70 shown in Fig. 4, the depression of the master-lever p would cause the toe z' of the arm z to strike the portion u^2 of the lever u , and rotate the latter counter-clockwise to the position shown in Fig. 5, and cause the lever u 75 to rotate the bell-crank v clockwise, in so doing pulling on the wire w and so operating the valve-arm w^2 as to close the valve. Upon the release of the master-lever it is 80 lifted to its normal position by the springs m , and the sliding plates j , and therewith the bars i , i , are returned to their normal position, as shown in Fig. 4.

Since the selector keys 2 are supported in their uplifted or normal position by the 85 arms z of the individual actuating mechanism, when a selector key has been operated, that is depressed as mentioned, it remains depressed until the arms z are again placed in their normal position; and hence the operator, by observing the position of the selector keys of the individual operating mechanisms, can tell which of the latter will be 90 thrown into action by the next depression of the master-lever. The series of selector 95 keys 2 are marked as convenient to designate the individual actuating mechanism which they control.

Connected to the lever, u , and extending through the front wall of the case, a , is a 100 rod x' having on its outer end a button x . By the latter the lever u may be rotated individually, independent of the other means. Pulling a button, x , out would rotate the connected lever u and the bell crank 105 v and cause a pull on the wire w .

From the construction of the lever u and the bell-crank v , it is apparent that when they are positioned as in Fig. 5 by the counter-clockwise rotation of the lever u the bell-crank, v , will be locked against reverse rotation until the lever u is rotated clockwise, then the bell-crank v will follow the movement of the lever u , and the parts will 110 resume the positions in which they appear in Fig. 4. The levers, u , can be rotated individually by the button x , and all the levers, u , may also be rotated by depressing the master-lever p after the arms, z , y , have been 115 properly positioned. Thus our actuating mechanism may be used to operate individual engines of the gang, by means of the individual keys x , and also to operate simultaneously certain units of the gang of engines, by previously selecting such units 120 through the medium of the selector keys 2, as mentioned, and following such action by the depression of the master-lever p . Since the buttons, x , will follow the movements 125 of the levers u , the operator, by observing 130

whether the buttons, x , are standing in or out, will be informed as to which of the units of the gang of engines have been thrown into action. And if any individual 5 actuating mechanism should have failed to act properly, the operator could then throw all individual actuating mechanisms back to their normal state by the lifting of the master-lever p , as mentioned, and then reset 10 the same by means of the selector keys 2.

In order to set a predetermined unit of the actuating mechanisms by a single operation, instead of by the selector keys 2 individually, 15 we provide the following means: Rock shafts, as 5, 13, (compare Figs. 3, 4 and 5) are journaled in brackets 6, provided at the front of the case α . The shaft, 5, is provided with a rigid arm 7, terminating in a button 8, and the shaft 13 has a rigid arm 9 having a button 10. Each shaft is provided 20 with cam-bars 11, located to engage with the pendent legs of certain selector keys 2. Hence, by pulling forward one of the buttons 8 or 10, or both, a plurality of selector 25 keys 2 will be operated simultaneously, and the corresponding units of the gang of engines may then be thrown into action simultaneously by the master-lever p .

In Fig. 5 we have shown our device as 30 connected to an electric switch of the circuit of an electromagnet. The knife switch, 16, is to be understood as located in the circuit of an electromagnetically operated valve; such, for example, as shown in our said co- 35 pending application. Said switch is held normally open by the spring 17, the rod, w , having a connection, w^e , with the switch handle. The action of our device is in other respects substantially the same as above 40 described. The buttons x , like the selector keys 2, must also bear suitable index characters for designating the engine units which they control.

The word engine is to be understood as including all forms of power driven devices. 45

We claim:

1. Actuating means for engine gangs comprising a master device; individual actuating mechanisms for the units of the gang 50 of engines, such mechanisms normally non-operable by the master device; key-operated means between such master device and said individual actuating means operating to place the latter in a state for being simultaneously thrown into action by the subsequent operation of the master device; and means operating to simultaneously restore all the individual actuating mechanisms to their normal state, such means operated by 55 the reverse movement of the master device.

2. Actuating means for engine gangs comprising a master device; individual actuating mechanisms for the units of the gang of engines, such mechanisms normally non-operable 60 by the master device; key-operated

means between such master device and said individual actuating means operating to place the latter in a state for being simultaneously thrown into action by the subsequent operation of the master device; the 70 individual actuating mechanism being adapted to become locked against return movement, when thrown into action, until restored to its normal state; and means operating to simultaneously restore all the individual actuating mechanisms to their normal state, such means operated by the reverse movement of the master device. 75

3. Actuating means for engine gangs comprising a master device; individual actuating mechanisms for the units of the gang of engines, such mechanisms normally non-operable by the master device; key-operated means for operating the actuating mechanism individually; key-operated 80 means between such master device and said individual actuating means operating to place the latter in a state for being simultaneously thrown into action by the subsequent operation of the master device; and means operating to simultaneously restore all the individual actuating mechanisms to their normal state, such means operated by the reverse movement of the master device. 85

4. Actuating means for engine gangs comprising a master device; individual actuating mechanisms for the units of the gang of engines, such mechanisms normally non-operable by the master device; key-operated means between such master device and said individual actuating means operating to place the latter in a state for being simultaneously thrown into action by the subsequent operation of the master device; means controlling a plurality of individual 100 actuating mechanisms, operating to place the same, simultaneously, in a state for being thrown into action by the subsequent operation of the master device; and means operating to simultaneously restore all the individual actuating mechanisms to their normal state, such means operated by the reverse movement of the master device. 105

5. Actuating means for engine gangs comprising a master device; individual actuating mechanisms for the units of the gang of engines, such mechanisms normally non-operable by the master device; key-operated means for operating the actuating mechanism individually; key-operated 115 means between such master device and said individual actuating means operating to place the latter in a state for being simultaneously thrown into action by the subsequent operation of the master device; the individual actuating mechanism being adapted to become locked against return movement, when thrown into action, until restored to its normal state; and means operating to simultaneously restore all the individual actuating mechanisms to their normal state, such means operated by the reverse movement of the master device. 120

6. Actuating means for engine gangs comprising a master device; individual actuating mechanisms for the units of the gang of engines, such mechanisms normally non-operable by the master device; key-operated 125

- dividual actuating mechanisms to their normal state, such means operated by the reverse movement of the master device.
6. Actuating means for engine gangs comprising a master device; individual actuating mechanisms for the units of the gang of engines, such mechanisms normally non-operable by the master device; key-operated means for operating the actuating mechanism individually; key-operated means between such master device and said individual actuating means operating to place the latter in a state for being simultaneously thrown into action by the subsequent operation of the master device; means controlling a plurality of individual actuating mechanisms, operating to place the same, simultaneously, in a state for being thrown into action by the subsequent operation of the master device; and means operating to simultaneously restore all the individual actuating mechanisms to their normal state, such means operated by the reverse movement of the master device.
- 25 7. In actuating means for engine gangs, a master device, individual actuating mechanisms for the units of the gang of engines, such mechanisms normally non-operable by the master device; key-operated means between such master device and said individual actuating means operating to place the latter in a state for being simultaneously thrown into action by the subsequent operation of the master device; and the individual actuating mechanism being adapted to become locked against return movement, when thrown into action, until restored to its normal state.
- 40 8. In actuating means for engine gangs, a master device, individual actuating mechanisms for the units of the gang of engines, such mechanisms normally non-operable by the master device; key-operated means between such master device and said individual actuating means operating to place the latter in a state for being simultaneously thrown into action by the subsequent operation of the master device; and means controlling a plurality of individual actuating mechanisms, operating to place the same, simultaneously, in a state for being thrown into action by the subsequent operation of the master device.
- 45 9. In actuating means for engine gangs, vertically reciprocable bars; a master lever reciprocating in said bars; individual actuating mechanism for each unit of the gang of engines, such mechanism comprising a rotatable lever and a bell-crank, rotated by such lever; arms pivoted on said reciprocable bars; means on the arms and on the rotatable lever for engaging the latter by one of the former, to thereby cause the forward and reverse rotation of the rotatable lever;
- 60 65 key-operated means for positioning the arms

to cause the operation of the actuating mechanism when the master lever is operated; and means operated by the reverse movement of the master lever and operating to simultaneously position all the arms for effecting only the reverse rotation of the lever.

10. In actuating means for engine gangs, vertically reciprocable bars; a master lever reciprocating in said bars; individual actuating mechanism for each unit of the gang of engines, such mechanism comprising a rotatable lever and a bell-crank, rotated by such lever; a key connected to the rotatable lever; arms pivoted on said reciprocable bars; means on the arms and on the rotatable lever for engaging the latter by one of the former, to thereby cause the forward and reverse rotation of the rotatable lever; key-operated means for positioning the arms to cause the operation of the actuating mechanism when the master lever is operated; and means operated by the reverse movement of the master lever and operating to simultaneously position all the arms for effecting only the reverse rotation of the lever.

11. In actuating means for engine gangs, vertically reciprocable bars; a master lever reciprocating in said bars; individual actuating mechanism for each unit of the gang of engines, such mechanism comprising a rotatable lever and a bell-crank, rotated by such lever; said rotatable lever and bell-crank being adapted to lock the latter against reverse rotation until the rotatable lever is reversed; arms pivoted on said reciprocable bars; means on the arms and on the rotatable lever for engaging the latter by one of the former, to thereby cause the forward and reverse rotation of the rotatable lever; key-operated means for positioning the arms to cause the operation of the actuating mechanism when the master lever is operated; and means operated by the reverse movement of the master lever and operating to simultaneously position all the arms for effecting only the reverse rotation of the lever.

12. In actuating means for engine gangs, vertically reciprocable bars; a master lever reciprocating in said bars; individual actuating mechanism for each unit of the gang of engines, such mechanism comprising a rotatable lever and a bell-crank, rotated by such lever; arms pivoted on said reciprocable bars; and means on the arms and on the rotatable lever for engaging the latter by one of the former, to thereby cause the forward and reverse rotation of the rotatable lever.

13. In actuating means for engine gangs, vertically reciprocable bars; a master lever reciprocating in said bars; individual actuating mechanism for each unit of the gang

of engines, such mechanism comprising a rotatable lever and a bell-crank, rotated by such lever; said rotatable lever and bell-crank being adapted to lock the latter 5 against reverse rotation until the rotatable lever is reversed; arms pivoted on said reciprocable bars; and means on the arms and on the rotatable lever for engaging the latter by one of the former, to thereby cause the 10 forward and reverse rotation of the rotatable lever.

14. In actuating means for engine gangs, vertically reciprocable bars; a master lever reciprocating in said bars; individual actuating mechanism for each unit of the gang 15 of engines, such mechanism comprising a rotatable lever and a bell-crank, rotated by such lever; a key connected to the rotatable lever; arms pivoted on said reciprocable 20 bars; means on the arms and on the rotatable lever for engaging the latter by one of the former, to thereby cause the forward and reverse rotation of the rotatable lever; and key-operated means for positioning the

arms to cause the operation of the actuating 25 mechanism when the master lever is operated.

15. In actuating means for engine gangs, vertically reciprocable bars; a master lever reciprocating in said bars; individual actuating mechanism for each unit of the gang 30 of engines, such mechanism comprising a rotatable lever and a bell-crank, rotated by such lever; arms pivoted on said reciprocable bars; means on the arms and on the rotatable 35 lever for engaging the latter by one of the former, to thereby cause the forward and reverse rotation of the rotatable lever; and key-operated means for positioning the arms to cause the operation of the actuating 40 mechanism when the master lever is operated.
